UNITED STATES PATENT OFFICE.

WILLIAM N. McCOMB, OF NEW YORK, N. Y.

ELECTRIC SIGN OR ILLUMINATING DEVICE.

No. 882,013.

Specification of Letters Patent. Patented March 17, 1908.

Application filed October 5, 1904. Serial No. 227,209.

To all whom it may concern:

Be it known that I, WILLIAM N. McCOMB, a citizen of the United States of America, and a resident of the city, county, and State of New York, have invented certain new and useful Improvements in Electric Signs or Illuminating Devices, of which the following is a specification.

My invention relates to electric signs or illuminating devices, and has for its main object the production of improved means whereby a unit block comprising a plurality of groups of sockets or receptacles can be quickly and easily adjusted to form any letter, symbol, numeral, or other device or to produce any illuminating effect desired. To this end I provide a plurality of adjustable sockets preferably arranged in groups and the groups preferably arranged in unit blocks. In the present construction, each unit block comprises a plurality of groups of sockets, adjustable in groups in one direction, say vertically, and adjustable individually at right angles to the line of adjustment of the group, say in a horizontal direction.

This broad invention may of course be embodied in any suitable form, though the specific construction shown in the accompanying drawings contains in itself valuable and novel features of construction. Preferably each unit block is in the form of a box adapted to receive a removable and interchangeable face plate (constituting the object to be illuminated) and containing a framework for suitably and adjustably supporting the sockets and forming, preferably, a conductor for the current to the lamps.

In the especial construction shown herein, two vertical standards or columns are provided, spaced a distance apart and supporting two cross bars forming socket supporting means for each group of sockets, on which the sockets are slidably mounted. The two standards are connected to the opposed poles of a source of supply of current while the two cross bars of each pair are in circuit with opposite standards, though supported on both by means of proper insulation devices. The cross bars are further so arranged that the opposed bars of adjacent pairs are of the same polarity so that when two groups of sockets are moved close together, the juxtaposition will cause no disturbance of the circuits. In some cases, as when forming script letters, it may be necessary or expedient to cause the letter or symbol or other device to

overlap from one unit block to the adjacent one. The parts are so arranged that proper adjustment can be had for effecting this; so that a letter or symbol may extend over more than one unit block with an uninterrupted illuminating effect. The socket used is especially constructed to meet the requirements of the general features of the device, and is provided with two contacting members extending into the interior of the socket and projecting outside the same so as to form a sliding contact both mechanical and electrical with the cross bars.

Other novel features of construction and combinations of parts will appear as the specification proceeds.

In the accompanying drawings I have embodied my invention in what I, at the present moment, consider the most desirable form.

In the said drawings: Figure 1 shows a unit block or box with the interior construction and arrangement of sockets exposed, embodying my invention. Fig. 2 is a sectional view on the line 2—2 of Fig. 1. Fig. 3 shows a blank face plate with lamps in position. Fig. 4 shows a face plate with the letter E properly illuminated. Fig. 5 shows a different form of the same letter, showing how the same unit block can be adjusted to make a smaller letter. Fig. 6 shows still a smaller form of the letter E. Figs. 7 and 8 are detail views of the individual sockets. Fig. 9 shows a sectional view of the insulating spool for supporting the cross bars. Fig. 10 shows particularly how script letters can be formed, and in general how an uninterrupted illuminating effect of a letter etc. extending over more than one unit block can be obtained. Fig. 11 shows how a picture or advertisement can be illuminated. Figs. 12 and 13 show how a crescent and a star can be formed.

Similar characters of reference indicate corresponding parts in the different views.

1 indicates a box forming the unit block, preferably made of standard size so as to be interchangeable, but which may of course be made of any size desired. Arranged within this box are two vertical standards 2 made of a conducting material and connected to the opposed poles of a source of supply of current as by means of the wires 3 and 4. Extending between the said vertical standards are a plurality of cross bars 5 and 6 arranged in pairs and suitably supported on the said vertical standards by means of the insulating

spools 7. These porcelain spools 7 are formed with two circumferential grooves 8 around which extend split brass rings 9. At the point where the two ends of the brass ring 5 meet, they are provided with transverse holes 10 through which extend the hooked ends of the cross bars 5 and 6, being secured in position by suitable means as the pins 11 or otherwise. Both the cross bars and split 10 ring are made of material forming an electric conductor. The two cross bars of each pair are in circuit with the opposed standards, one cross bar being electrically connected to one standard and the other cross bar to the 15 other standard by means of a metallic spring 12 or otherwise. The polarity of opposite cross bars of the adjacent pairs is alike so that when the groups are moved close together the juxtaposition will create no electrical 20 disturbance.

The cross bars form socket supporting means and are provided with horizontally disposed slots 13 and the sockets are provided with two contacting members 14 and 15, 25 extending into the interior of the sockets as at 16 and 17 and projecting outside the same into the slot 13 as at 18 and 19 so as to enable the current to pass through the lamps at any point to which they may be adjusted. At 30 each end the slots 13 are enlarged as at 20 so that the sockets can be removed. A suitable face plate 21 is inserted in front of the box 1, as shown at 21 with the proper device to be illuminated, and with the proper number of 35 holes to admit of the lamps 22 being inserted.

In Fig. 3 I have shown a blank face plate with all the lamps in position. In Fig. 4 a face plate containing the letter E is shown with the proper number of holes to admit 40 of the lamps being placed in position. In Figs. 5 and 6 a smaller sized letter is shown formed by means of a different face plate and the proper adjustment of the lamps.

It will be understood that the sockets 45 which it is not desired to use are simply left without lamps, and the remainder properly adjusted in this instance vertically in groups and individually in a horizontal direction. The insulating spools are held in the position 50 to which they have been adjusted by friction, or other means may be employed for this purpose if desired.

Sometimes it may be desirable to have one symbol or letter or other device extend over 55 more than one unit block, in such a manner as to produce an uninterrupted illuminating effect. In Fig. 10 I have shown how this may be accomplished. A number of unit blocks are placed together and the face plates 60 of the same are so decorated or designed as to have the letter or other symbol extend

over more than one unit block. The sockets in the adjacent unit blocks are then arranged so as to correspond with each other to obtain a unitary or uninterrupted illuminating 65 effect. In this way it will be understood that any style of letter or character can be formed, or, more properly, illuminated, including the Egyptian, Roman, full block, ornamental, and script type, as well as 70 upper and lower case letters in any type, any single number desired of plain or special design. Also other characters, emblems, designs, frames or border lights for pictures, trade-mark, posters, or any reading matter 75 or "catch lines."

From the foregoing it will be easily understood that by simply changing the face plate and adjusting the sockets, a new sign or advertisement can be formed by means of the 80 same unit.

What I claim is:

1. In an electric illuminating device, the combination with a plurality of sockets, of means for adjusting the same in groups in 85 one direction and means for adjusting them individually in a direction at right angles to the group adjustment.

2. In an electric illuminating device, the combination with a plurality of sockets, of 90 means for adjusting the same in groups in a vertical direction, and means for adjusting them individually in a horizontal direction.

3. In an electric illuminating device, a unit block composed of a plurality of sockets, 95 means for adjusting the same in groups in one direction, and means for adjusting them individually in a direction at right angles to the group adjustment.

4. In an electric illuminating device, a 100 unit block composed of a plurality of sockets, means for adjusting the same in groups in a vertical direction, and means for adjusting them individually in a horizontal direction.

5. In an electric illuminating device, the 105 combination with two standards spaced a distance apart and connected to opposite poles of a source of supply of electricity, cross bars connecting the said standards and adjustably mounted upon the same and arranged in pairs, one cross bar of each pair being in circuit with one standard and the other cross bar being in circuit with the other standard, and one or more sockets adjustably mounted upon the cross bars having 110 115 electrical connection with the same.

Signed at New York this 3rd day of October 1904.

WILLIAM N. McCOMB.
